UNITED STATES PATENT OFFICE

STEPHEN FAITH, OF CHICAGO, ILLINOIS

INITIAL OR MONOGRAM CAP FOR GOLF CLUB SHAFTS

Application filed July 2, 1931. Serial No. 548,408.

My invention relates to an initial or monogram cap for golf club shafts and, generally speaking, is concerned with the provision of a device of this kind which readily may be 5 properly positioned on and attached to the club shaft, which protects the end of the club shaft, which presents good appearance, and which is capable of being economically manufactured.

10 One of the features of the invention is the provision of special means in the grip or handle end of a club shaft for facilitating the application of the cap to the club and co-operating with the cap firmly to hold the latter 15 in the desired position when applied.

Other features, objects and advantages of the invention will appear as the following detailed description progresses.

In the accompanying drawings illustrating 20 my invention,

Fig. 1 is a view in axial section of the grip or handle end of a golf club shaft of wood which has been provided with improvements 25 facilitating the application of an initial or monogram cap thereto;

Fig. 2 is a plan view of the upper end of the shaft portion of Fig. 1;

Fig. 3 is a top plan view of an initial or monogram cap suitable for application to a 30 club shaft provided with the improvements of Figs. 1 and 2;

Fig. 4 is a side elevational view of the cap;

Fig. 5 is a view similar to Fig. 1 illustrating 35 how the friction plug of the shaft may be depressed prior to the application of the cap to the shaft;

Fig. 6 is an axial sectional view illustrating the cap in the first stage of its application to 40 the club shaft;

Fig. 7 is a slightly enlarged view, partly in section and partly in elevation, illustrating the cap and plug as they appear when the cap is finally applied to the club shaft; and

Fig. 8 is an axial sectional view of a modification of the present invention, the several parts in this view being shown as they appear 45 just before the screw of the cap is threaded down against the movable plug of the club shaft.

Similar characters of reference refer to similar parts throughout the several views.

At 10 I have illustrated the handle or grip portion of a golf club shaft of wood. As herein illustrated, the upper end of the shaft is 55 slightly convex, as indicated at 11. The usual grip wrapping of leather or other suitable material is indicated at 12.

Formed in the upper end of the shaft is an axial blind bore, *a* which preferably is of uniform diameter throughout its length, this bore ordinarily, in my practice of the invention, being approximately one-eighth of an inch in diameter and something less than an inch in length.

Firmly pressed into the bore *a* and lying flush with the convex end 11 of the shaft is a short cylindrical plug *b*, which preferably is formed of a hard material, such for instance as commercial fiber, which will not 70 be penetrated or substantially penetrated by the screw of the initial or monogram cap, presently to be described. The plug *b* preferably is of a color contrasting with the color of the wood of the shaft to give the upper 75 end of the shaft a good appearance prior to the application of the cap, and to facilitate the immediate location of the plug when it is to be depressed prior to the application of the cap.

Figs. 1 and 2 illustrate the club shaft and its fiber plug *b* as they usually will appear when sold by the manufacturer of the clubs, the idea of the present invention being to provide the club shaft with means for facilitating the ready application of an initial or monogram cap which usually will be applied by the retailer or by the ultimate purchaser after the latter has determined the initial or monogram which he wishes to have appear upon his clubs.

The cap *c* preferably is provided with a convex upper surface 13, a concave lower surface 14 and a milled or knurled peripheral edge 15. Carried by the cap *c* and preferably formed integral therewith and projecting downwardly from the center of its concave face is a wood screw *d* of a diametrical size suitable for threaded engagement with the 85 90 95 100

bore *a* of the club shaft and of a length substantially less than said bore *a*.

Formed on or in the upper surface of the cap *c* may be an initial, together with any 5 suitable decorative design or marking, all as is clearly indicated in Fig. 3.

After a golfer has selected a cap *c* bearing the initial or monogram design which he prefers, the plug *b* of the club shaft to which 10 the cap is to be applied is slightly depressed within the bore *a* as illustrated in Fig. 5. This depressing of the plug *b* may be accomplished by any make-shift instrument such as a nail, but I prefer to employ a shouldered 15 tool of the kind indicated at 16. The wood screw *d* of the cap is then applied to the open end of the bore *a* and is threaded down into the same until the point of the screw engages the friction plug *b*. As illustrated in Fig. 6, 20 this occurs while there is still a substantial clearance between the opposed surfaces 11 and 14 of the cap and shaft respectively. Threading of the wood screw *d* into the bore *a* now is continued, this further threading of 25 the screw into the bore being substantially resisted but not prevented by the fiber friction plug *b*. The cap is turned down until it has the snuggest fit with the convex upper end of the club shaft which is consistent with the 30 monogram being left at the desired position with respect to the shaft and its head,—most players preferring to have the initial or monogram so located that it readily may be read when the club is gripped as in play. The friction plug *b* is of considerable advantage in enabling the initial or monogram to be adjusted in the desired position without there being any serious danger of the cap becoming loose 35 from the club shaft by reason of failure to screw the cap against the club shaft with the utmost force. The effect of the friction plug upon the screw, after the screw has engaged the plug, is to keep the upper surfaces 40 of the several convolutions of the thread of the screw tightly in engagement with the upper surfaces of the female thread formed in the wood,—an effect which is akin to that which results when the head of a screw is brought tightly against a member into which 45 the screw is threaded.

If desired, I may place within the blind bore *a* a short helical spring *e* which is of a length such that its compression by the plug *b* does not commence until the latter has been 55 engaged and started on its further downward movement as a result of its engagement by the pointed end of the screw *d* of the cap. This arrangement, of Fig. 8, enables the plug *b* continuously to exert upon the screw *d* an 60 upward pressure which magnifies the tendency and ability of the plug to prevent casual loosening of the cap from the club shaft, even though the cap may not be threaded down upon the club shaft to the greatest extent which would be possible if the proper po-

sitioning of the initial or monogram were not taken into consideration.

By "monogram cap" as these words are used in the appended claims, I mean to include any cap carrying an initial, monogram or other design or identification mark individual to the owner of the club to which the cap is attached. 70

While I have illustrated the improvements of the present invention applied to a golf club shaft of wood, it will be understood that the invention may be applied to metal shafts if desired. 75

Having thus described and illustrated my invention, what I claim as new and desire to secure by Letters Patent of the United States, is:

1. A club shaft having a blind bore in its handle end, a plug located in said bore, and a monogram cap provided with a screw 85 adapted to be threaded into said bore against the resistance afforded by said plug.

2. A club shaft having a blind bore in its handle end, a friction plug located in said bore, and a monogram cap for said end of the 90 shaft provided with a screw adapted to be threaded into said bore against the frictional resistance of the plug.

3. A club shaft of wood having a blind bore in its handle end, a friction plug of a hard 95 material such as fiber located in said bore, and a monogram cap for said end of the shaft, said cap carrying a wood screw adapted to be threaded into said bore against the frictional resistance of said hard plug. 100

4. A club shaft having a blind bore in its handle end, a monogram cap adapted to lie over and protect said end of the shaft, a screw carried by the cap adapted to be threaded into said blind bore, and means within said 105 bore cooperating with the screw to hold it against loosening as the result of casual shocks.

5. A club shaft having its handle end adapted for the reception of and threaded engagement with a monogram cap, there being a blind bore in said handle end, and a friction plug fitted in and closing said bore, said friction plug being adapted to recede into the bore to permit threading into the bore of the 115 screw of a monogram cap.

6. A club shaft having its handle end adapted for the reception of and threaded engagement with a monogram cap, there being a blind bore of uniform diameter in said handle end, a friction plug fitted in and closing said blind bore, said friction plug being adapted to recede into said blind bore under the pressure of the screw of a monogram cap when 120 said screw is threaded into said bore.

7. In the attachment to a club shaft of a monogram cap provided with an attaching screw the method which consists in forming a blind bore in the shaft, inserting a closure plug in said bore, depressing the plug to ac- 125

commode the insertion of the screw, and threading the screw into the bore against the frictional resistance of the plug.

8. A club shaft provided with a blind bore 5 in its handle end, a plug in said bore, a monogram cap for said shaft provided with a screw adapted to be threaded into said bore and when so threaded to move said plug inwardly, and a spring in said blind bore adapted to be put under compression when the plug 10 is forced inwardly by the pressure of said screw.

In witness whereof, I hereunto subscribe my name this 27th day of June, 1931.

STEPHEN FAITH.
